UNITED STATES PATENT OFFICE.

JOSEPH B. HOLDEN, OF SYRACUSE, NEW YORK, ASSIGNOR TO REMINGTON TYPE-WRITER COMPANY, OF ILION, NEW YORK, A CORPORATION OF NEW YORK.

TYPEWRITING-MACHINE.

1,386,256.

Specification of Letters Patent.

Patented Aug. 2, 1921.

Application filed February 24, 1921. Serial No. 447,533.

To all whom it may concern:

Be it known that I, JOSEPH B. HOLDEN, citizen of the United States, and resident of Syracuse, in the county of Onondaga and State of New York, have invented certain new and useful Improvements in Typewriting-Machines, of which the following is a specification.

My invention relates to typewriting machines and more particularly to the carriage construction and means for mounting and supporting the same.

The invention is shown embodied in a Remington portable machine of the general character disclosed in part in the patent to A. W. Smith, #1,342,513, dated June 8, 1920, and in the application of J. B. Holden, Sr., #851,197, filed January 3, 1920.

The main object of the present invention, generally stated, is to provide simple and effective means of the character specified which contributes materially to the production of a small, light, compact portable machine, and yet provides sufficient strength and rigidity to prevent distortion of the parts and assure a proper correlation thereof and a proper operation of the machine under varying conditions.

From certain aspects the present invention may be regarded in the nature of an improvement on the construction shown in the above mentioned Holden application.

To the above and other ends which will hereinafter appear my invention consists in the features of construction, arrangements of parts and combinations of devices set forth in the following description and particularly pointed out in the appended claims.

In the accompanying drawings, wherein like reference characters indicate corresponding parts in the different views,

Figure 1 is a fragmentary vertical fore-and-aft sectional view of the machine; showing enough of the machine to illustrate my invention in its embodiment therein.

Fig. 2 is a detail fragmentary horizontal sectional view of a portion of the same, taken on the line 2—2 of Fig. 1 and looking in the direction of the arrow at said line.

Fig. 3 is a detail fragmentary perspective view showing a portion of the carriage and its support and some of the associated parts.

Fig. 4 is a detail fragmentary perspective

view of the stop means for preventing the carriage from being lifted off its support, together with some of the parts associated therewith.

The machine comprises an outer sheet metal inclosing frame 1, in which is fixed a second sheet metal frame that supports the various working parts of the machine, and which may be removed bodily with all of said working parts from the inclosing frame. The inner supporting frame comprises sheet metal side plates 2 united by a front comb plate 3, a hollow cross rod 4 and other parts not shown.

Supported by the inner frame is a case shift or carriage supporting frame which may be said to comprise two sections, one in the nature of a sheet metal frame and the other comprising a casting 7 detachably secured to the sheet metal frame. This last mentioned frame comprises two parallel side bars 5 arranged parallel with and close to the side plates 2. The bars 5 extend longitudinally fore-and-aft of the machine and each is provided with an inwardly bent integral horizontally disposed supporting flange or portion 6 on which one end of the casting 7, comprising the main body portion of the carriage support proper, is detachably mounted by screws 8. The forward ends of the bars 5 are pivoted at 9 to the lower ends of parallel upright arms or links 10. These links are pivotally supported on inwardly projecting pins or spindles 11 secured to the side plates 2. Cotter pins 12 extend through openings 13 in the spindles 11, and when removed enable the links to be detached from said spindles.

The casting 7 is preferably made of aluminum, and the screws 8 preferably engage in threaded openings in nuts 14 of a harder metal received in countersunk openings in the body of the casting, to more effectively connect the casting to the sheet metal section of the shift frame. The casting 7 is formed with a pair of depending ears 15 near each end thereof. The upper end of an upright arm 16 is received in the space between each pair of ears 15 to pivotally connect the casting thereto by a removable screw pivot 17. The pair of parallel upright arms 16 are fixedly connected at their lower ends to a rock shaft 18. The reduced ends 19 of this shaft are received in bearing openings in the side

plates 2 of the supporting frame, and thus the two-part shift frame is supported at its rear end for a rearward case shift movement from the normal lower case position shown in Fig. 1, to the upper case position. From an inspection of Fig. 1 it will be understood that the construction and arrangement of the parts are such that the upright arms 16 and the shaft 18 are disposed beneath the carriage, and that when the carriage is shifted to the upper case position the arm 16 will be substantially dead-centered with reference to the printing line and the axis of the platen, so that blows of the type against the top of the platen will be directed lengthwise of the supporting arms 16 and resisted by their fixed pivots, or rock shaft 18, thus reducing or preventing any vibration of the platen that might ordinarily be produced by the blows of the types thereon.

The casting 7 is formed at intervals throughout the length thereof, and along its front edge portion, with integral upstanding lugs or arms 20. An upstanding sheet metal plate 21 is secured to the front face of these lugs by screws 22, which pass through openings in the plate 21 and in the lugs 20, and are threaded into relatively hard metal nuts 23, in order to firmly secure the plate 21 to the casting. The upper edge portion of the plate 21 is bent throughout the length thereof to form a roller bearing way 24 having two bearing surfaces or tracks 25 and 26 at substantially right-angles to each other, to coat with crossed bearing rollers 27 and 28 respectively. Depending lugs 29 are formed on the casting, and to the lower faces of these lugs is secured a sheet metal plate 30, held to the lugs by screws 31 which pass through openings in the plate 30 and in the casting, and are threaded into relatively hard metal nuts 32 received in countersunk openings in the casting. The plate 30 extends rearwardly from the casting, and is bent along its free edge portion to form a roller bearing way 33 having bearing faces 34 and 35 at substantially right-angles to each other for coöperation with crossed bearing rollers 36 and 37 respectively.

The carriage comprises a sheet metal bed or main body portion 38 bent to form a horizontally disposed base portion and an upstanding portion 39 which extends up in front of a platen 40 supported by sheet metal end plates 41 secured to the base portion of the carriage. The upper free edge portion of the upstanding part 39 of the carriage bed is bent to form an inverted substantially U-shaped roller bearing way 42 having two bearing faces 43 and 44 at substantially right-angles to each other, to coat with the bearing rollers 27 and 28 respectively. It will be seen that the carriage plate 38, bent as shown and described to form the way 42, is adapted to inclose the

bearings and bearing rollers at the front of the carriage, and cover the same and constitute a protective housing therefor against the entrance of falling particles of dust or grit.

The forward edge portion of the plate 38 extends in front of and overlaps the bearing plate 21, and is provided with teeth 45 formed therein to constitute a rack which extends throughout the length of the carriage. In the present instance this rack constitutes a back spacing rack for coöperation with suitable back spacing devices such, for example, as those disclosed in the application of Herbert E. Bridgwater, filed Jan. 8, 1921, Sr. No. 435,974. In the present instance this rack is entirely separate and distinct from the feed rack of the carriage, as will hereinafter more clearly appear. The rear edge portion of the carriage plate 38 is bent throughout the length thereof to form a bearing roller way 46 having two bearing faces 47 and 48 at substantially right-angles to each other and adapted to coat with the crossed bearing rollers 36 and 37 respectively. It will be seen that the way 46 is of inverted substantially U-shaped formation in cross section to cover and inclose the roller bearing at the rear of the carriage and exclude dust and grit therefrom.

In order to prevent the carriage from being lifted off its support, I have provided means, shown more particularly in Figs. 1 and 4, which comprise a sheet metal strip 49 with feet or ears 50 and with stops or fingers 51 projecting therefrom. Each ear 50 is tapped to receive the end of a screw 52 which passes through a fore-and-aft slot 53 in the base of the plate 38. By these means the stops 51 are adjustably secured to the bottom of the plate 38, and extend therefrom with their contact faces parallel with and beneath the way 33 of the plate 30 secured to the carriage support. The stops 51 are normally free from contact with the bottom of the way 33 but limit the upward movement of the carriage relatively thereto, and prevent the carriage from being lifted off its support.

From the foregoing description it will be understood that the sheet metal bed plate of the carriage has its main body portion substantially L-shaped in cross section; that the carriage support is likewise substantially L-shaped in cross section, that the various lateral bends in the bed plate 38, and which extend throughout the length thereof, tend to stiffen the carriage structure and enable a comparatively light sheet metal stock to be used for the carriage bed and main body portion of the carriage; that the aluminum casting for the carriage support gives the requisite stiffness and rigidity to the construction without adding to the weight thereof; that each of the plates 21 and 30 is

provided with double bends therein which extend throughout its length, providing a construction which is substantially Z-shaped in cross section and further adds to the rigidity of the construction, and that the carriage receives a roller bearing support beneath the same and beneath the platen, and also receives a roller bearing support at a higher elevation and in front of the carriage 10 and forward of the platen, forming a very effective roller bearing support for the carriage of a top strike machine in which the invention is shown embodied in the present instance.

15 The carriage support may have a case shifting movement transmitted thereto by any suitable means, those disclosed in the present instance being similar to the means disclosed in the hereinbefore mentioned 20 Holden application. Briefly stated, these case shift means comprise a case shift key lever 54, a link 55, bell crank lever 56, operative on a pin 57 carried by a bar 5 of the shift frame, the parts being limited 25 in their shifting movements by stops 58 and 59, and returned to normal position by spring 60. Each spring is connected at one end to an ear 61 integral with and depending from the associate flange 6, and is connected at the other end to a pin 62 projecting 30 from a side plate 2. The shift key lever, as in the construction disclosed in said Holden application, controls a locking lever 63 which coacts with the pin 57 to prevent 35 a vibration of the shift frame and platen in the normal position of the parts.

In the present instance I have mounted 40 rollers 64 on shouldered pivot screws threaded into tapped openings in the flanges 6, so that the rollers are supported beneath said flanges and coact with the side plates 2 of the supporting frame and prevent any lateral vibration of the carriage supporting 45 shift frame in any position to which the carriage may be shifted, and during the shifting movement thereof. A case shift lock key 65 and locking member 66 are also provided, as in the construction disclosed in said Holden application, to lock the shift 50 key lever 54 down when its key 67 is depressed.

The feed of the carriage under the pull 55 of its spring drum (not shown) is controlled by suitable feed dogs (not shown), which coact with a feed rack 68 secured by screws 69 to a plate 70, pivoted at 71 to bracket plates 72, secured to the base plate of the carriage.

It will be seen that so far as the parts 60 shown and described are concerned a removal of the screws 8 and 17 enable the carriage supporting member 7, together with the carriage mounted thereon, to be detached and removed from the machine as a single 65 unit and that said parts, as a single unit,

may as readily be replaced in the machine when desired.

All of the nuts, 14, 23 and 32 may have their peripheries scored, corrugated or milled as shown at 23^a in Fig. 3, so as to 70 engage the walls of the countersunk openings in which the nuts are received and thus lock each nut against turning when the associated screw is threaded into or out of the nut. 75

The employment of the rock shaft 18 beneath the carriage and with its rigidly connected arms 16 directly and firmly pivoted to the rigid casting 7 provides a firm construction that prevents the carriage support from being deflected, distorted or skewed and helps to maintain the parts properly correlated and to assure a proper positioning of the carriage in its line of travel at all times. 80

85 What I claim as new and desire to secure by Letters Patent is:—

1. In a typewriting machine, the combination of a carriage comprising a sheet metal bed plate which has its main body 90 portion substantially L-shaped in cross section and has its edge portions bent to form two covered bearing roller receiving ways each presenting two track faces one at substantially right angles to the other, a carriage support substantially L-shaped in cross section and having a cast metal body portion and roller receiving ways disposed opposite to the ways in the carriage bed, both ways on the carriage support being formed by 95 bends in sheet metal plates detachably secured to the cast metal body portion, and bearing rollers in said ways. 100

2. In a typewriting machine, the combination of a carriage comprising a sheet metal 105 bed plate which has its main body portion substantially L-shaped in cross section and has its edge portions bent into substantially inverted U-shaped form to provide two covered bearing roller receiving ways, a substantially L-shaped carriage support comprising a cast metal body portion, two sheet metal plates bent into substantially Z-shaped form in cross section to provide two bearing roller ways disposed opposite to the 110 ways on the carriage, means for detachably fixing said plates to the cast metal body portion, and bearing rollers received in said ways. 115

3. In a typewriting machine, the combination of a carriage comprising a sheet metal bed plate which has its main body 120 portion substantially L-shaped in cross section and has its edge portions bent into substantially inverted U-shaped form to provide two covered bearing roller receiving ways, a substantially L-shaped carriage support comprising a cast metal body portion, two sheet metal plates bent into substantially Z-shaped form in cross section to pro- 125

vide two bearing roller ways disposed opposite to the ways on the carriage, means for detachably fixing said plates to the cast metal body portion, bearing rollers received in said ways, and a rack formed in the edge of one of said U-shaped ways.

4. In a typewriting machine, the combination of a carriage comprising a sheet metal bed plate which has its main body portion substantially L-shaped in cross section and has its edge portions bent to form two covered bearing roller receiving ways, a carriage support substantially L-shaped in cross section and having two bearing roller receiving ways disposed opposite those in the carriage bed plate, and a rack formed in one edge of the bed plate and extending forward of the upright member of the L-shaped carriage support.
- 10 5. In a typewriting machine, the combination of a carriage comprising a sheet metal bed plate which has its main body portion substantially L-shaped in cross section and has its edge portions bent into substantially inverted U-shaped form to provide two covered bearing-roller receiving ways, a carriage support substantially L-shaped in cross section and provided with sheet metal roller bearing ways that are bent substantially Z-shaped in cross section, bearing rollers in said ways, and a finger or stop fixed on the bed plate of the carriage and extending beneath one of said ways on the carriage support to prevent the carriage from being lifted off its support.

6. In a typewriting machine, the combination of a carriage support comprising a cast metal body portion with upstanding lugs formed integral therewith and an upstanding sheet metal plate secured to said lugs and formed with a roller bearing way therein, and a second sheet metal plate secured to said cast metal body portion and formed with a roller bearing way therein; a platen carriage comprising a sheet metal bed formed with roller bearing ways therein; and bearing rollers intermediate the ways in the carriage bed and said support.

7. In a typewriting machine, the combination of a carriage support comprising a cast metal body portion with upstanding lugs formed integral therewith and an upstanding sheet metal plate secured to said lugs and formed with a roller bearing way therein, and a second sheet metal plate secured to said cast metal body portion and formed with a roller bearing way therein; a platen carriage comprising a sheet metal bed formed

with roller bearing ways therein, the carriage support and carriage bed each being substantially L-shaped in cross section and having their upright members extending up in front of the platen, and bearing rollers intermediate the ways in the carriage bed and said support.

8. In a typewriting machine, the combination of a carriage support comprising a cast metal body portion having integral upstanding lugs thereon, an upstanding sheet metal plate bent to provide a roller bearing way therein and secured to said lugs, and a second sheet metal plate bent to provide a roller bearing way and secured to the bottom of said cast metal body portion; a carriage comprising a sheet metal body portion bent to provide roller bearing ways disposed opposite the ways in the carriage support; and bearing rollers in said ways.

9. In a typewriting machine, the combination of a carriage support comprising a cast metal body portion having integral upstanding lugs thereon, an upstanding sheet metal plate bent to provide a roller bearing way therein and secured to said lugs, and a second sheet metal plate bent to provide a roller bearing way and secured to the bottom of said cast metal body portion; a carriage comprising a sheet metal body portion bent to provide roller bearing ways disposed opposite the ways in the carriage support; bearing rollers in said ways; and a platen carried by said carriage and extending below the roller bearing way in said upstanding plate and over the way in said second plate.

10. In a typewriting machine, the combination of a carriage having roller bearing ways, a carriage support the main body portion of which is made of aluminum, sheet metal plates having companion roller bearing ways for those on the carriage, bearing rollers between said ways, and means for detachably securing said plates to the aluminum body portion of the support, said means comprising nuts of harder metal received in countersunk openings in said aluminum body portion and held against rotation therein and screws which pass through openings in said plates and body portion and are threaded into said nuts.

Signed at Syracuse, in the county of Onondaga and State of New York this 21 day of Feb., A. D. 1921.

JOSEPH B. HOLDEN.
